DESIGN FOR A SHELF BRACKET

Francis E. Elmer, Bronson, Mich., assignor to
L. A. Darling Company, Bronson, Mich., a cor-
poration of Delaware

Application March 29, 1937, Serial No. 68,453

Term of patent 7 years

To all whom it may concern:

Be it known that I, Francis E. Elmer, a citizen
of the United States and resident of Bronson,
county of Branch, State of Michigan, have in-
vented a new, original, and ornamental Design
for a Shelf Bracket, of which the following is a
specification, reference being had to the accom-
panying drawing forming a part thereof.

Fig. 1 is a perspective view of a shelf bracket
showing my new design; Fig. 2 is a top plan view
thereof, and Figs. 3 and 4 are side and outer end
views, respectively, thereof.

I claim:

The ornamental design for a shelf bracket, sub-
stantially as shown.

FRANCIS E. ELMER.
